UNITED STATES PATENT OFFICE.

SAMUEL A. NEIDICH, OF EDGEWATER PARK, NEW JERSEY, ASSIGNOR TO THE AMERICAN MULTIGRAPH COMPANY, OF CLEVELAND, OHIO, A CORPORATION OF OHIO.

TYPE-CASE.

1,119,859.

Specification of Letters Patent.

Patented Dec. 8, 1914.

Application filed April 22, 1912. Serial No. 692,358.

To all whom it may concern:

Be it known that I, SAMUEL A. NEIDICH, of Edgewater Park, in the county of Burlington and State of New Jersey, have invented a certain new and useful Improvement in Type-Cases, whereof the following is a specification, reference being had to the accompanying drawings.

This invention relates to a case which includes stationary type holders comprising vertical type font channels between parallel channel bars, each channel having at its lower end an abutment which normally upholds, in said channel, type having recesses in their opposite sides engaged by flanges on said bars. Said abutments are movable so that the type may be permitted to gravitate one at a time from said channels into a composing stick. As hereinafter described, said abutments have lever shanks which are pivoted on a horizontal axis above the abutments and extend above their axis in coöperative relation with respective springs which not only normally maintain them in position to support the type in the channels but constitute detents respectively adapted to detain the type above the lowermost one in each channel when its abutment is thrust rearwardly to permit the escape of the lowermost type from that channel. Such movement of the abutments is conveniently effected by a coöperative composing stick when the latter is presented in the precise position to receive the lowermost type. I find it convenient to provide at the lower end of each channel a wedge shaped socket having lateral and longitudinal sides converging inwardly to fit a wedge shaped projection on the composing stick, so that the latter may be readily placed in proper coöperative relation with the type channel to receive type therefrom; the arrangement being such that when the wedge shaped projection on the composing stick is thrust into the wedge shaped socket of any selected channel, the abutment thereat is thrust rearwardly to release the lowermost one type which thereon gravitates into the composing stick while the remainder of the type are detained in that channel by engagement of its spring detent with the next to the lowermost type in that channel. Said composing stick conveniently includes a longitudinally slotted metal tube; the opposite edges of the slot being adapted to fit in the

recesses in the opposite sides of the type which slide between them.

Said case also includes a movable type holder comprising a rotary drum arranged to support a flexible type chase, forming the subject matter of Letters Patent of the United States #989,277 granted to me April 11, 1911, and having a plurality of type channel bars, forming channels to which the type may be transferred from said font channels of the case.

My invention comprises the various novel features of construction and arrangement hereinafter described.

In the drawings: Figure I is a front elevation of a case embodying my invention. Fig. II is a vertical sectional view of said case, taken on the line II, II in Fig. I. Fig. III is a fragmentary vertical sectional view taken on the line III, III in Fig. I. Fig. IV is a fragmentary sectional view taken on the line IV, IV in Fig. III. Fig. V is a fragmentary vertical sectional view taken on the line II, II in Fig. I, but showing the abutment displaced by the composing stick; the latter being in position to release and receive the lowermost type. Fig. VI is a fragmentary front elevation of said composing stick in the same position as in Fig. V. Fig. VII is a fragmentary sectional view taken on the line VII, VII in Fig. V. Fig. VIII is an elevation of a plate carrying a series of the detent springs.

In said figures; the case comprises the left and right hand frame standards 1 and 2 which are connected in rigid relation by the front frame standard 3, the rear frame standard 4 and the top rest plate 5.

The type channel bars 7, 8 and 9 are disposed in parallel relation in respective panels, being held in spaced relation by cross bars 11 and 12 having recessed seats for said channel bars in which the latter are rigidly held by the edges of said seats swaged against them; said bars having flanges 14 adapted to occupy grooves 15 in the opposite sides of rows of type 16 extending in the channels 17 between said flanges. Said recessed cross bars 11 and 12 being preferably formed of die cast metal which is comparatively soft are respectively reinforced by plates 19 and 20 connected therewith by screws 21 and 22; said plates projecting beyond the ends of said bars in engagement

with the lugs 24 on said frame standards 1 and 2; the arrangement being such that said panels of channel bars may be readily removed from the type case when desired.

5 Said plates 20 have recesses 26 arranged to register with the respective channels 17, and the fulcrum rods 27 extend in said plates 20 transversely to said channels to pivotally support the levers 28 intermediate of their 10 length, in the respective recesses. Each of said levers has at its lower end an abutment 30 adapted to obstruct the end of the adjacent channel 17 and normally prevent the escape of type 16 therefrom. The comb 15 plates 31 held between said cross bars 12 and plates 20 by said screws 22 have, in unitary relation, a series of parallel detent springs 32 as best shown in Fig. VIII. Said springs 20 respectively extend in said recesses 26 and press the opposite ends of said levers 28 to present said abutments in operative position, to obstruct the ends of the channels 17 and uphold the type 16 therein as shown in Figs. II and VI.

25 As best shown in Fig. V the free end of each spring 32 terminates a distance from the adjacent abutment 30 greater than the extent of one type 16 in said channel and is adapted to engage and detain the type to 30 which it is opposed, when said lever 28 is tilted to remove said abutment from the end of said channel.

Index bars 35 are carried by said plates 20 extending transversely with respect to said 35 channels 17 and recesses 26, being connected with said plates by the screws 36, and, the abutment ends of said levers 28, the edge of said index bar 35 opposed thereto, and the side walls of said recesses 26 in said plate 40 20 are converged inwardly to form wedge shaped sockets 37 at the ends of said channels 17.

I find it convenient to operate said abutment levers to release the type from said 45 type case and compose the same by means of the composing stick shown in Figs. V and VI, which includes a longitudinal slotted metal tube 40 having a tip 41 slotted in alignment with the slot in said tube; the opposite 50 edges of said slots forming a pair of parallel guiding members spaced like the longitudinal flanges 14 on said channel bars to occupy grooves in the opposite sides of a row of type extending in the channel 43 between 55 them. Said composing stick has the wedge shaped projection 45 extending transversely with respect to said channel 43 adapted to fit said wedge shaped sockets 37 when said composing stick is in proper coöperative relation with said channel bars 7, 8 or 9 to tilt one of said abutments 30, release the type immediately adjoining it and receive said type; whereby, when any of said levers 28 is tilted to retract its abutment 30 and permit 60 the escape of a single type 16 from the adja-

cent channel 17, its spring 32 is operated to detain the other type in said channel. Said composing stick 40 being held like a pencil in the hand of the operator is conveniently provided with the bridge plate 46 as a rest 70 for the forefinger of the operator and, the opposite end of said stick may be provided with an abutment lever and detent spring such as above described, or, it may be provided with a tip embodying a stationary 75 abutment and a recess immediately adjoining the same of such size as to permit the escape of a single type at right angles to the channel 43 like the composing stick described and claimed in Letters Patent of the 80 United States 955,534 granted to me April 19, 1910. Said channel bars 7, 8 and 9 are tapered at their upper ends as shown in Fig. II so that the type 16 may be readily slid 85 into said channels 17 from the composing stick aforesaid, with which they have been picked from the case as above described; the operation of distributing the type from the composing stick to the type case being similar to that of discharging the type from the 90 type case to the composing stick as illustrated in Fig. V; such distribution being conveniently effected while the operator's hand rests on the plate 5.

As indicated in Fig. I said index bars 35 95 are conveniently marked with the characters of the type stored in the respective channels above them, and, I also find it convenient to provide similar index bars 48 at the upper ends of said channels to facilitate the distribution of the type therein. Said bars 48 are conveniently supported by the levers 49 pivoted at 50 in the frame standards 1 and 2 so that they may be upturned out of the way when it is desired to remove said panels. 100 Normally said levers 49 and bars 48 are retained in the position shown in Fig. 2 by set screws 51 extending through said frames 1 and 2 in engagement with said levers.

I do not desire to limit myself to the precise details of construction and arrangement above described as it is obvious that various modifications may be made therein without departing from the essential features of my invention as defined in the appended claims. 115

I claim:—

1. The combination with a series of parallel channel bars having flanges adapted to occupy grooves in the opposite sides of rows of type extending in the channels between 120 them; of a cross bar having recessed seats for said channel bars, holding them in spaced relation; a socket plate extending transversely to said channel bars, having recesses arranged to register with the respective channels; a fulcrum rod extending in said socket plate transversely to said channels; levers in the respective recesses, fulcrumed intermediate of their length on said rod, each having at one end an abutment 125

130

- adapted to obstruct the end of the adjacent channel and normally prevent the escape of type therefrom; a comb plate, held between said cross bar and socket plate, having, in 5 unitary relation, a series of parallel detent springs respectively extending in said recesses and pressing the opposite ends of said levers; the free end of each spring terminating a distance from the adjacent abutment 10 greater than the extent of one type in said channel and being adapted to engage and detain the type to which it is opposed, when said lever is tilted to remove said abutment from the end of said channel; and, an index 15 bar carried by said socket plate extending transversely with respect to said channels and recesses; the abutment ends of said levers, the edge of said index bar opposed thereto, and the walls of said socket plate 20 between them, being converged inwardly to form wedge shaped sockets.
2. The combination with a series of parallel channel bars having flanges adapted to occupy grooves in the opposite sides of rows 25 of type extending in the channels between them; of a cross bar having recessed seats for said channel bars, holding them in spaced relation; a socket plate extending transversely to said channel bars, having recesses arranged to register with the respective channels; levers in the respective recesses, fulcrumed intermediate of their 30 length, each having at one end an abutment adapted to obstruct the end of the adjacent channel and normally prevent the escape of type 35 therefrom; a comb plate, held between said cross bar and socket plate, having, in unitary relation, a series of parallel detent springs respectively extending in said recesses and pressing the opposite ends of said levers; the free end of each spring terminating a distance from the adjacent abutment greater than the extent of one type in said channel and being adapted to engage and 40 detain the type to which it is opposed, when said lever is tilted to remove said abutment from the end of said channel; an index bar carried by said socket plate extending transversely with respect to said channels and recesses; the abutment ends of said levers, the edge of said index bar opposed thereto, and the walls of said socket plate between them, being converged inwardly to form wedge shaped sockets.
5. The combination with a series of parallel guide bars adapted to occupy grooves in the opposite sides of rows of type extending in the channels between them; of levers each carrying an abutment wider than and

adapted to obstruct the end of the adjacent channel and normally prevent the escape of type therefrom; and wedge shaped sockets longitudinally below the respective levers and substantially alining with the channels.

4. The combination with a series of parallel guide bars adapted to occupy grooves in the opposite sides of rows of type extending in the channels between them; of levers each carrying an abutment wider than and adapted to obstruct the end of the adjacent channel and normally prevent the escape of type therefrom; a wedge shaped socket at the end of each channel; whereby a composing stick having a projection may be adapted to fit said sockets, tilt said abutments and receive said type.

5. The combination with a series of parallel guide bars adapted to occupy grooves in the opposite sides of rows of type extending in the channels between them; of levers each carrying an abutment adapted to obstruct the end of the adjacent channel and normally prevent the escape of type therefrom; and sockets longitudinally below the respective levers and substantially alining with the channels, the sockets being wedge shaped in a direction transverse to the length of the channels.

6. The combination with a series of parallel guide bars adapted to occupy grooves in the opposite sides of rows of type extending in the channels between them; of levers each carrying an abutment adapted to obstruct the end of the adjacent channel and normally prevent the escape of type therefrom; and, a stationary wedge shaped socket at the end of each channel facing transversely to the length of the channel and adapted to receive abutment tilting means.

7. In a type case, the combination, with inclined typeholding bars, a cross bar near the lower end of the typeholding bars, a socket plate carried by the cross bar, a series of levers pivotally mounted on the socket plate and having forward and upward projections adapted to engage beneath the type channels, and upwardly flaring facing recesses in the socket plate located below the levers adapted to be occupied by a tool moving diagonally downward onto the levers.

In testimony whereof, I have hereunto signed my name at Burlington, New Jersey, this sixteenth day of April, 1912.

SAMUEL A. NEIDICH.
